CLAIM

The ornamental design for a dog toy, as shown and described.

DESCRIPTION

FIG. 1 is a front, top and right side perspective view of the dog
toy showing my new design;

FIG. 2 is a front elevational view thereof;

FIG. 3 is a rear elevational view thereof;

FIG. 4 is a right side elevational view thereof, the left side
elevational view being a mirror image of the right side eleva-
tional view;

FIG. 5 is a top plan view thereof; and,

FIG. 6 is a bottom plan view thereof.

The broken lines shown in FIGS. 1, 5 and 6 depict environ-
mental subject matter, are for illustration only and form no
part of the claimed design.
